Attest.

UNITED STATES PATENT OFFICE.

SAMUEL SPILLER, OF ROCKHAMPTON, QUEENSLAND, AUSTRALIA, ASSIGNOR OF ONE-HALF
TO EDWARD STAMP, OF ROCKHAMPTON, AUSTRALIA.

BURNER-NIPPLE PRICKER AND CLEANSER.

No. 890,883.

Specification of Letters Patent.

Patented June 16, 1908.

Application filed December 31, 1906. Serial No. 350,173.

To all whom it may concern:

Be it known that I, SAMUEL SPILLER, a subject of the King of Great Britain and Ireland, &c., residing at Rockhampton, in the 5 State of Queensland, Commonwealth of Australia, have invented certain new and useful Improvements in Burner-Nipple Prickers and Cleansers; and I do hereby declare the following to be a full, clear, and exact description of the invention, such as will enable others skilled in the art to which it appertains to make and use the same.

The object of this invention is to provide an improved pricker and cleanser for trimming the nipples of burners as of acetylene 15 gas and others liable to become choked by the products of combustion. Many burners become useless or defective in operation if not cleansed. Wire has been used for cleaning 20 such nipples, but this invention provides a new combination of parts for holding the cleaning member, which need not be a wire in all cases, and for allowing of its insertion and adjustment, the whole forming a simple 25 pocket tool. The said tool, which has no part adapted to be lost, is illustrated in the accompanying drawings, in which

Figure 1 is a side elevation of the tool open, with two wires, and with another cleaning 30 member (which is dispensed with in some cases) as described below. Fig. 2 is a side elevation of the parts in Fig. 1, the tool being however closed. Fig. 3 shows the parts in Fig. 1 in plan view, in slightly modified form, 35 and omitting the wires. Figs. 4 and 5 show details.

In these drawings *a, b* are the two sides and *c, d* the two ends of a sheath formed by taking a blank of sheet metal or material and bending it on its longitudinal axis so that 40 there is a longitudinal recess *a'* between the said sides which is closed on three sides. Side *a* projects higher than *b*. The recess at end *d* is wide, but at end *c* narrow. Riveted 45 at *e* some distance from the narrow end *c* is a bar or blade *f* which may be closed or opened like the blade of a pocket knife, but which has no spring. Blade *f* may be of any suitable material, its outer end being provided 50 with a wire holder formed by bending over a part *g* provided in the blank from which the blade is made, a doubled part being thus made. This doubled or folded portion is the wire or pin holding and adjusting means. 55 In some cases one platinum wire simply

would be used; but in Figs. 1, 2 two (*i, j*) are shown with long ends *i', j'* in reserve, these ends being bent out of the way along the blade *f*.

In Fig. 4 a single wire is shown bent to 60 form two prickers or pins *i², j²*. When there is scope for using two or more pins simultaneously, to cleanse burners arranged in pairs, this invention is useful, as any particular distance between the pins or wires is readily 65 insured, and the part *g* whether folded on the blade from the end of the latter as in Figs. 3 to 5, or from another edge as in Figs. 1 and 2, can be readily made tight upon any wire by a slight hammer blow. In some cases I provide 70 a small regulating screw *g²* passing freely through a hole in the part *g* and screwing into a threaded hole in the blade *f* so as to insure the desired tight grip, and allow of loosening when desired—see Figs. 3 and 4. Screw *g²* 75 draws part *g* tight against the wire or cleaning member. When the wires are of greater length than the width of the blade the excess length is readily kept in reserve for use (by degrees) in each case as the cleansing end 80 becomes worn, and needs cutting off.

In Figs. 1 and 2 holes *g¹* are shown in part *g*, and through these holes the wires pass, but wire is also shown held by a folded member *g*, which has no holes; see Fig. 4. 85

Fig. 4 shows a loop *l²* in a wire which has pin points *i², j²*, the loop being for cleaning burners having slotted nipples.

In Fig. 5 a thin slit cleaning blade *l* is shown secured in the fold under member *g* and 90 with its rear end *l¹* turned over part *g*.

In Figs. 1 and 2 the blade end *k* is made thin to serve as a slit cleanser, the folded part being located lower on the blade. *h* is a projection on blade *f* to act as a stop to abut on 95 side *b* and prevent the blade closing so far as to damage the pins *i, j*, or other cleansing part, while at the same time these parts are protected when the tool is closed. This will be clear from Fig. 2 in which a part of side *b* 100 appears broken out for clearer illustration. It is important that the pricking ends of the wires may be easily regulated in length, as the blade *f* then acts as a stop to prevent the wires being pushed in too far, and damaging 105 the delicate burner. The wide end of recess *a'* receives the thick part of blade *f*. Pivot *e* is sufficiently removed from the end *c* of the rear side (see Fig. 1) of the sheath to allow 110 that end to act as a stop to prevent the blade

being opened back too far. Fig. 1 shows the fully opened position.

The illustrations are not to be regarded as limiting this invention to the sizes, proportions, or numbers of parts used in the construction.

What I do claim as my invention and desire to secure by Letters Patent of the United States is:—

- 10 1. A tool sheath, a blade pivoted thereto and adapted to be inclosed therein, said blade having a portion folded upon itself and wires held by said folded portion.
- 15 2. A tool sheath, a blade pivoted thereto, said blade having a portion folded upon itself, a screw for regulating the position of the folded portion relative to the blade and wires adjustably held by said folded portion.

3. A tool sheath having one side higher than the other, and one end wider than the other, and a blade or bar pivoted to it, and adapted to be inclosed therein, a fold in the blade, and a cleaning member held by the said fold as described.

4. A device of the class described comprising a blade having a portion folded upon itself, said folded portion having holes therein and cleaning wires passing through the holes and held by said folded portion.

In witness whereof I have hereunto set my hand in the presence of two witnesses.

SAMUEL SPILLER.
